UNITED STATES PATENT OFFICE.

EMIL A. POPCKE, OF NEW YORK, N. Y.

HAND-PRESS FOR PRINTING WALL-PAPER.

SPECIFICATION forming part of Letters Patent No. 746,152, dated December 8, 1903.

Application filed July 28, 1903. Serial No. 167,267. (No model.)

To all whom it may concern:

Be it known that I, EMIL A. POPCKE, a citizen of the United States, residing at New York city, (Bronx,) county of New York, and 5 State of New York, have invented certain new and useful Improvements in Hand-Presses for Printing Wall-Paper, of which the following is a specification.

This invention relates to a hand-press for 10 printing a multicolored ground or pattern on wall-paper in such a way that the colors will blend into each other.

In the accompanying drawings, Figure 1 is 15 a perspective view of a hand-press embodying my invention. Fig. 2 is a section through the upper part thereof on line 2 2, Fig. 1; and Fig. 3, a similar section showing the stencil raised and the printing-block in position.

The letter *a* represents a slush-box supported on feet *a'* and adapted to contain a 20 body of water that acts as a cushion. Upon ledges *a'* of box *a* is supported a frame *b*, provided with a water-tight canvas bottom *b'*. The frame *b* contains the print-cloth *c*, made 25 of felt or other material, said cloth being sunk below the top of the frame and slush-box. To the upper edge of box *a* is hinged at *d'* a movable stencil-plate *d*, which is adapted to be supported upon the top of frame *b*. 30 The plate *d*, when lowered, is thus placed into parallelism with the print-cloth, but at a distance therefrom, a free-space *e*, Fig. 2, intervening between them. The stencil-plate *d* is composed, essentially, of connected narrow 35 upright ribs arranged to form a suitable pattern, such pattern corresponding either to the groundwork or to the pattern which is to be printed upon the wall-paper. The drawings show the stencil arranged to print a groundwork formed of a number of ovals *f* to be 40 printed in one color and of surrounding irregular fields *g* to be printed in another color.

In use the stencil is lowered upon the frame *b*, Fig. 2, and then the paint is applied to the 45 print-cloth *c* by a brush projected through the stencil-plate. Thus, say, a dark color is applied through the ovals *f* and a light color

is applied through the fields *g*. As the stencil does not contact with the print-cloth, but is raised off the same, the boundary lines between the dark and light colors will disappear on the print-cloth, and consequently such colors will blend. After the cloth *c* has been prepared in the manner described the stencil-plate *d* is swung up, Fig. 3, and the 50 print block or roller *h* is lowered upon the print-cloth. Thus the blended colors will be conveyed to the print-block, from which the 55 wall-paper is printed in the usual manner.

It is obvious that in lieu of printing the 60 background of the wall-paper the stencil-plate may be of such a configuration as to print the pattern. In that case the background is first printed by the use of one stencil and then the pattern is printed upon the 65 background by the use of a second stencil.

It will be seen that by my invention I can produce multicolored designs on wall-paper in a quick and accurate manner and so that the colors will blend into a harmonious pattern. 70

What I claim is—

1. A hand-press for wall-paper composed of a slush-box, an inclosed frame having a bottom, a print-cloth supported thereby, and 75 a movable stencil-plate above said cloth, substantially as specified.

2. A hand-press for wall-paper, provided with a print-cloth, a movable stencil-plate, and means for supporting said plate at a distance above the print-cloth, substantially as specified. 80

3. A hand-press for wall-paper, composed of a slush-box, an inclosed frame having a canvas bottom, a print-cloth within the frame, 85 a stencil-plate, and means for supporting said plate at a distance above the print-cloth, substantially as specified.

Signed by me at New York city, (Manhattan,) New York, this 27th day of July, 1903. 90

EMIL A. POPCKE.
